UNITED STATES PATENT OFFICE

170,115

BICYCLE

Nettie M. Essary, Big Spring, Tex.

Application November 19, 1952, Serial No. 22,370

Term of patent 7 years

(Cl. D90—8)

To all whom it may concern:

Be it known that I, Nettie M. Essary, a citizen of the United States, residing at Big Spring, in the county of Howard and State of Texas, have invented a new, original, and ornamental Design for a Bicycle, of which the following is a specification, reference being had to the accompanying drawing, forming part thereof.

Fig. 1 is a side elevational view of a bicycle, showing my new design.

Fig. 2 is a top plan view of the same.

Fig. 3 is a view in elevation looking toward the other side of said bicycle.

Figs. 4 and 5 are front and rear elevational views, respectively, of the bicycle.

I claim:

The ornamental design for a bicycle, as shown.
NETTIE M. ESSARY.
